United States Patent Office

Des. 183,397

Patented Aug. 19, 1958

183,397

CAN OPENER

George A. Lehmann, Ferguson, Mo., assignor to The Dazey Corporation, St. Louis, Mo., a corporation of Missouri

Application March 25, 1957, Serial No. 45,411

Term of patent 7 years

(Cl. D22—2)

In the drawing:

Fig. 1 is a side elevational view of a can opener, showing my new design;

Fig. 2 is an elevational view showing the side opposite to Fig. 1; and

Fig. 3 is a top plan view of the can opener shown in Fig. 1.

I claim:

The ornamental design for a can opener, as shown.
